ABRADING DEVICE

Frank Cooke, North Brookfield, Mass., assignor
to American Optical Company, Southbridge,
Mass., a voluntary association of Massachusetts

Application August 25, 1952, Serial No. 306,161

7 Claims. (Cl. 51—209)

1

This invention relates to improvements in abrading devices and has particular reference to an improved ring-type abrading tool for use in generating curved surfaces on articles such as lens blanks.

One of the principal objects of this invention is to provide an abrading device embodying an annular abrading tool adapted to be mounted for rotatable engagement with an article such as a lens blank to be surfaced and adapted to abrade the article along a predetermined path of generation, said tool comprising a pair of concentric annular abrading members respectively carrying abrasive particles thereon of different abrading characteristics and disposed one within the other, with one of the members being adjustable with respect to the other member in a direction longitudinally of the tool, and with the adjoining sides of the members being provided throughout with interfitting irregularities of a controlled size and shape extending alternately across said path of generation.

Another object is to provide an abrading tool comprising a pair of concentric annular abrading members respectively carrying abrasive particles thereon of different abrading characteristics and disposed one within the other, with one of the members being adjustable with respect to the other member in a direction longitudinally of the tool, and with the adjoining sides of the members being provided throughout with interfitting scalloped shaped surfaces whereby portions of said respective surfaces will extend alternately across said path of generation at acute angles with respect to the tangent of said path of generation and thereby greatly improve the texture of the resulting abraded surface.

Another object is to provide an abrading tool of the above character wherein one of said annular abrading members will be provided with abrasive particles of relatively coarse mesh and the second annular abrading member will be provided with abrasive particles of relatively fine mesh whereby the abrading members may be used respectively for rough and fine grinding operations and wherein the sizes of the scallops and/or the thickness of the fine grinding member is increased relative to the size of the scallops and/or the thickness of the rough grinding member by an amount to substantially balance the wear and durability of said respective members.

Still another object is to provide an abrading tool of the above character embodying annular abrading members one disposed within the other and provided with interfitting portions so arranged as to provide restricted openings between said annular members at spaced intervals throughout the path of generation to permit the flow of a lubricant therethrough.

Other objects and advantages of the invention

2

will become apparent from the following description taken in connection with the accompanying drawings, in which:

Fig. 1 is a front elevational view of abrading apparatus embodying the present invention;

Fig. 2 is a side elevational view of the apparatus shown in Fig. 1, part of which is taken in section along line 2—2 of Fig. 1;

Fig. 3 is an enlarged vertical sectional view taken substantially on line 3—3 of Fig. 2;

Fig. 4 is a horizontal sectional view substantially on line 4—4 of Fig. 3;

Fig. 5 is a fragmentary front elevational view partly in section illustrating the method of fine grinding a convex surface on a lens blank;

Fig. 6 is a view generally similar to Fig. 5 illustrating particularly the method of fine grinding a concave surface on a lens blank;

Fig. 7 is a perspective view of an abrading tool of the preferred type;

Fig. 8 is an enlarged face view of the abrading surface of the tool shown in Fig. 7;

Figs. 9, 10, and 11 are enlarged face views similar to Fig. 8 illustrating modifications of the abrading tool;

Fig. 12 is a fragmentary side elevational view partly in section of the mechanism for adjusting the tool-carrying head; and

Fig. 13 is a diagrammatic illustration of the manner in which a scallop approaches an area of the article to be abraded.

Prior to the present invention, it has been the usual practice in the ophthalmic industry to form the desired curved surfaces on articles such as lens blanks by abrading methods requiring the use of at least two separate machines. One of the machines was provided with a rough abrading tool and an article such as a lens blank was previously secured to a suitable holder and then placed in this machine and the surface thereof was initially abraded to substantially the shape desired. The second machine was provided with a fine abrading tool. The article being surfaced was transferred from the first machine to the second machine and then abraded to substantially the final shape and surface texture desired by the fine abrading tool. Subsequent polishing operations provided the exact optical surface desired of the article.

It is apparent that with the foregoing method, two separate abrading machines were necessary for performing the individual rough and fine grinding operations, thus requiring considerable floor space, and possibly requiring different operators, with consequent added operational expense.

Considerable time was involved in transferring the articles from one machine to another with the added existent possibility that the articles might be chipped or otherwise damaged or broken during transfer. In addition to the above undesirable features was the fact that resultant surfaces

produced on the articles might be inaccurate due to human error in making the separate adjustments of the two machines. Also the possibilities for errors were increased due to the fact that the articles might be accidentally dislocated with respect to the holder when being transferred.

Therefore, it is one of the prime factors of the present invention to provide a single machine which will perform both the rough and fine grinding operations successively without necessity of transferring the articles between operations, which machine requires but one setting and embodies a dual abrading tool which is comprised of individual portions for performing the respective rough and fine grinding operations as a substantially single continuous operation, thereby resulting in a decrease in the amount of floor space and operational expense required and also decreasing the possibilities of error.

Referring more particularly to the drawings wherein like characters of reference designate like parts throughout the several views, apparatus embodying the invention comprises a housing 15 having a head 16 pivotally attached thereto by a relatively large bearing 17. A complete description of the machine is given in the specification forming a part of United States Patent No. 2,286,361 issued on June 16, 1942 to Lloyd W. Goddu. For details of the construction and operation of this machine which are not included in the following description, reference is made to the above-mentioned patent.

The housing 15 has a work-supporting spindle 18 therein (Fig. 2), the spindle 18 being rotatably supported in a sleeve 19 longitudinally movable in a bearing 20 carried by a web 21 internally of the housing 15. The spindle is supported adjacent its opposed ends by ball bearings 22 and 23 mounted internally of shouldered recesses 24 and 25 in the sleeve 19. The spindle 18 is held against longitudinal movement in the sleeve 19 by a plate 26 attached to the upper end of the sleeve 19. The plate 26 overlies the bearing 22 which, in turn, engages an annular shoulder 27 formed on the spindle 18. The spindle 18 is provided with a reduced end portion 28 fitted within a sleeve-like bearing member 29 supported internally of spaced ball bearings 30 and 31. The end portion 28 is keyed to the sleeve-like bearing 29 so as to rotate as an integral unit and to permit longitudinal movement of said end portion 28 internally of the sleeve-like bearing 29. The sleeve-like bearing 29 is held in desired relation with the ball bearings 30 and 31 by means of a lock nut 32 adjacent the upper end thereof and a plate 33 adjacent the lower end thereof, the plate 33 being secured to the end of the bearing 20 by suitable means such as screws 34. The sleeve-like bearing 29 has a drive pulley 35 secured thereto which is connected by a belt 36 and similar pulley 37 to a motor 38 supported internally of the housing 15. Operation of motor 38 will, through pulley 37, belt 36, pulley 35 and sleeve-like bearing 29, cause rotation of the spindle 18.

The upper end of the spindle 18 is provided with a threaded portion 39 on which a shield 40 is mounted. The spindle, directly above the threaded portion 39, is provided with a tapered end 41 which is adapted to support a block adapter 42 which is retained thereon as by set screw 43 and which carries thereon a block 44.

A lens blank 45 or similar article to be abraded is secured to the block 44 by pitch 44a or other suitable adhesive and is thus adapted to be rotated

with the block 44 and adapter 42 when the spindle 18 is rotated.

The spindle 18 and consequently the lens blank 45 are vertically adjustable by means of a rack 46 which is provided on the sleeve 19. The rack 46 has a portion extending into an elongated groove 47 formed in the bearing 20 and, through its engagement with the side walls of the groove 47, prevents rotation of the sleeve 19. The rack 10 is in constant mesh with a pinion 48 located within an enlarged portion 49 of the bearing 20. The pinion 48 is carried by a shaft 50 (Figs. 1 and 2) which extends through a side wall of the housing 15 and which has a hand lever 51 attached to its outer end. Manual rotation of the hand lever 51 will cause rotation of the pinion 48 and will consequently cause upward or downward movement of the rack 46, sleeve 19 and spindle 18, and thus of the lens blank 45. The upper end of 20 the sleeve 19 is provided with a flange 52 which is adapted to engage the upper end of the bearing 20 for limiting the extent of downward movement of the sleeve 19.

The motor 38 is so constructed as to also rotate 25 a pulley 53 (Fig. 2) by means of a flexible shaft 54 connected thereto, the pulley 53 being rotatably secured internally of the upper end of the head 16 and being connected with a second spaced similarly mounted pulley 55 by a belt 56. 30 The second pulley 55 is thus adapted to rotate with pulley 53 and is keyed to a tool-supporting spindle 57 as illustrated at 58 whereby the spindle 57 will also rotate. The spindle 57 is mounted in ball bearings 59 and 60 which are supported 35 in shouldered annular recesses 61 and 62 internally of a sleeve or quill 63 which is carried within a vertical bore 64 (Fig. 2) formed in a support 65 provided in the head 16. A collar 66 (Fig. 3) is fixed to the spindle 57 adjacent the ball bearing 60 and thus prevents undesired raising of the spindle 57 in the sleeve 63. A nut 67 is attached to one end of the spindle 57 adjacent the pulley 55 and prevents dislocation of the pulley 55 which, in turn, rests against ball bearing 59. The nut 66 is threaded onto the threaded end 68 of the spindle 57 and thus is adapted to take up any looseness or end thrust play in the spindle 57 and is adjustable to compensate for wear of a dual abrading tool 69 carried by the opposed tapered end 70 of the spindle 57.

An annular hub 71 is provided with a tapered opening 72 therein which is adapted to fit upon and frictionally bind with the tapered end 70 of the spindle 57. The hub 71 is provided with a peripheral flange 73 to which is soldered or otherwise secured an annular abrading member 74 forming a part of the dual tool 69. Within the flange 73 is positioned a disc-like supporting member 75 having a hub 76 slidably positioned within an enlarged portion 77 of the opening 72 in the annular hub 71. A second annular abrading member 78 is soldered or otherwise attached to the disc-like member 75 and closely interferes with the inner surface of the outer abrading member 74 (Figs. 3, 5, 6 and 7).

The inner abrading member 78 is adapted to move longitudinally of the tool with respect to the outer abrading member 74. A stud 79 is threaded into the disc-like member 75 and slidably extends upwardly into a bore 80 formed in the annular hub 71 (Figs. 3 and 5). A coiled spring 81 is positioned over the stud 79 between a head 82 on the end of the stud 79 and a shoulder 83 formed by a reduced portion of the bore 80, the spring 81 serving to continually urge the disc-

like member 75 and inner abrading member 78 upwardly to a position where the abrading surface of the inner member 75 will be retracted with respect to the abrading surface of the outer member 74.

To locate the inner abrading member in extended position beyond the plane of the abrading surface of the outer member 74, a shaft 84 is extended longitudinally through the spindle 57 and has its lower end positioned against the hub 76 of the disc-like member 75. The upper end of the shaft 84 is located in a recess 85 provided therefor in the inner end of a knob 86 which is threadedly inserted in the adjacent portion of the housing 87 of the head 16 (Figs. 1, 2 and 3). Downward threading of the knob 86 will cause downward movement of the shaft 84 which, in turn, will cause the disc-like member 75 and inner abrading member 78 to move downwardly against the inherent tension of spring 81. Upon turning the knob 86 in the opposite direction, the spring 81 will cause retraction of the inner abrading member 78 as described and will also simultaneously raise the shaft 84.

The knob 86 is provided thereon with a cylinder 88 having graduations 89 thereon (Fig. 1) which are adapted to register with an indicator 90 secured to the housing 87 whereby the extent of movement of the inner abrading member 78 with respect to outer member 74 is visually indicated.

In accordance with this invention, the abrading surfaces of each of the annular abrading members 74 and 78 are provided with particles of abrading material such as diamonds or other suitable material, the inner member 78 preferably being of relatively coarse mesh for the rough grinding of the lens blank and the outer member 74 preferably being of relatively fine mesh for the fine grinding.

To position the tool 69 and lens blank 45 in abrading relation, the hand lever 51 is manually operated to raise the work-supporting spindle 18 and, consequently, the lens blank 45 into position against the tool 69. Means such as a weight 91 (Fig. 1) suspended by a cord 92 which is wound on a pulley 93 carried by the shaft 50 is provided for continually urging the spindle 18 and lens blank 45 upwardly as the surface of the lens blank 45 is being abraded by the tool 69. However, in order to limit the extent of the upward movement of the spindle 18 and consequently to control the depth of the cut and amount of material being removed from the surface of the lens blank 45, an elongated threaded stop member 94 is carried by a support 95 carried by the head 16 and is adapted to be engaged at one end by the flange 52 on the sleeve 19 as the spindle 18 moves upwardly. Adjustment is accomplished by threading the stop member 94 upwardly or downwardly by means of the knob 96 provided therefor on the opposite end of the member 94.

In order to provide the desired surface curvature on the lens blank 45, the head 16 is adapted to be adjusted about the axis of the bearing 17 and locked in adjusted angular position by means of a screw device 97 as described in the aforementioned Goddu patent. The head 16 is thus adapted to be tilted to a desired position determined by a suitable degree scale 98 and vernier 99 (Fig. 1).

It is to be understood that the head 16, when pivoting on the bearing 17, pivots about an effective center 100 which is preferably located in axial alignment with the center of curvature of the

abrading surfaces of the abrading members 74 and 78. The center 100 is also located on the axis of rotation A—A of the lens blank (Figs. 3, 5 and 6). The pitch diameter of the tool 69 is slightly larger than the radius of the lens blank 45. Thus, with the head 16 tilted as described and the tool 69 in engagement with the lens blank 45, the motor 38 may be operated to rotate both the tool and lens blank and cause the tool 69 to abrade the surface of the lens blank 45.

The lens blank 45 will be abraded by the tool 69 along a predetermined substantially annular path or line of generation. This path is indicated in Figs. 8, 9, 10, 11 and 13 as line 101, which line 15 may be a continuation of any point in the path forming a circle having a center 103 on the axis of the tool.

In accordance with this invention, however, the meeting or adjoining sides of the annular abrading members 74 and 78 are provided with a plurality of closely interfitting irregularities preferably in the form of scallops 74a and 78a respectively (Figs. 7 and 8). The scallops 74a on the outer abrading member 74 extend inwardly to overlie the line of generation 101 and the scallops 78a on the inner abrading member 78 extend outwardly to overlie the line of generation 101, the recesses between the scallops on the respective members, however, being disposed on the same side of the line of generation 101 as the major portion of the members. Thus, in face elevation the line of juncture between the abrading members 74 and 78 appears, as shown in Figs. 8 through 11, as an endless serpentine line weaving continuously alternately back and forth across the line of generation 101.

In setting up the device for rough grinding of the lens blank 45, the inner abrading member 78 is extended slightly beyond the abrading surface of the outer member 74. The inner member 78 carries the coarse particles of abrading material and is illustrated in Fig. 7 in greatly exaggerated extended relation to the outer fine grinding member 74. Thus, with the inner rough grinding member 78 extended, this will cause the center of curvature of the abrading surface thereof to move slightly in a direction toward the lens blank 45 to the position indicated by numeral 102 in Fig. 3. This center 102 will also be displaced slightly with respect to the axis line A—A. Such displacement of the center 102 of the abrading surface of the rough grinding member will, however, cause no resultant error since after the rough grinding operation has been completed, the inner member 78 will be retracted and the outer fine grinding member 74 will provide the lens blank 45 with the exact surface curvature required. The center 100 of the fixed abrading member 74 will remain on the axis line A—A and will still be concentric with the axis about which the head 16 is adjusted. This operation will compensate for any error introduced by displacement of the center 102 of the inner tool 78.

One feature of the tool construction which is especially desirable is the fact that the fine grinding member 74 is mounted on relatively fixed supporting means while the rough grinding member 78 is mounted on the movable parts which would be most likely to become loose or slack. However, since the fine grinding member 74 is relatively fixed, any error caused by looseness of the parts supporting the inner rough grinding member 78 will be compensated for. This, of course, would not be true if the rough and fine grinding members were reversed.

Another desirable result of providing the composite tool with abrading members 74 and 78 constructed as described is that all of the abrading of the individual inner and outer members will be performed along a single path of generation without requiring any adjustment other than the slight longitudinal adjustment of the rough grinding member to extend or retract its abrading surface as described with respect to the surface of the fine grinding member.

An additional and particularly desirable accomplishment of an abrading tool constructed and arranged in accordance with this invention is that the resultant surfaces formed on the lens blanks are of improved texture. This is believed to be accomplished by the provision of the scallops 74a and 78a which are preferably shaped as curved segments. It will be apparent that as the tool is rotated, while in engagement with the lens blank, the leading edge of the actual effective abrading area of each scallop 74a and 78a will approach a particular surface area to be abraded at an acute angle to the tangent of the line or path of generation at the point at which the leading edge of the abrading area crosses the line or path of generation. This is illustrated in Fig. 13 wherein the leading edge 124 of the abrading portion of a scallop 78a is shown as being at an acute angle X to the tangent 125 of the path or line of generation 101 at the point at which said leading edge 124 of the scallop 78a crosses said path or line of generation 101.

This will cause a shearing action to take place in removing material from the lens blank rather than the chiseling action which would occur if the advancing edge of the cutting area was disposed in a plane normal to the tangent of the line of generation. Thus, when the abrading areas of the tool approach the material to be removed in the above manner and continue to "slither" across the surface, the resultant surface texture is of high quality.

Although the foregoing description refers particularly to the formation of a convex surface on a lens blank 45, this invention is readily adapted to forming concave surfaces. Referring to Fig. 6, a lens blank 104 is attached to a concave block 105 by a layer of pitch 106. The head 16 is tilted about the center 100 in the opposite direction which will angle the tool 69 so that the abrading surface of the fine grinding member 74 at the point which is on the axis line A—A about which the work rotates, will be lower than the diametrically opposed abrading surface thereof by an amount in accordance with the curvature to be generated and the angle of tilt of the head as indicated on scale 98.

The present invention is adapted to the use of tools 69 of various diameters and, therefore, means is provided for adjusting the tool-supporting device so as to position the center 100 about which the head is tilted on axis line A—A. To accomplish this, the top of the housing 15 is provided with slideways 107 on which a table 108 carrying the head 16 is adapted to move in a horizontal direction (Figs. 2 and 12). The table 108 carries on its underside a drive shaft 109 which is journaled in depending portions 110 of the table 108 and is threaded through an upwardly extending portion 111 of the housing 15. A hand crank 112 is mounted on the outer end of the shaft 109. Thus, manual rotation of the crank 112 will cause rotation of the shaft 109 and will consequently move the table 108 and head 16 along the slideways 107. The adjustment is vis-

ually indicated by a pointer 113 on the side of the table 108 which registers with a scale on the side of the housing 15.

It is known that a fine grinding tool of the presently described type will wear somewhat faster than a rough grinding tool. Therefore, it is sometimes advisable to form the tool as shown in Fig. 10 wherein the outer fine grinding member 114 with scallops 115 which have a longer contact area along the line of generation 101 than the scallops 116 on the inner rough grinding member 117.

Another modification is shown in Fig. 11 wherein the outer fine grinding member 118 is thicker than the inner rough grinding member 119 which will also compensate for additional wear of the fine grinding member 118.

In instances wherein it is desired to supply an oil or coolant as a lubricant through the abrading tool, supply means such as described in the aforementioned Goddu patent may be connected with a longitudinal bore 119 (Fig. 5) in the tool adjusting shaft 64 whereby the lubricant may flow downwardly therethrough and through bores 120 and 121 in the hub extension 76 into the space 122 between the upper surface of the disc-like member 75 and annular hub 11. Then the lubricant can flow through one or more spaces 123 (Fig. 9) formed adjacent the ends of the scallops 74a and 78a to the surfaces of the abrading members 74 and 78 and surface of the lens blank 45.

It is particularly pointed out that a machine constructed and arranged according to the foregoing description will perform both rough and fine grinding operations successively in one substantially single continuous operation without necessity of moving the articles between the rough and fine grinding operations and with only one adjustment or setting up operation being required.

From the foregoing description, it will be apparent that all of the objects and advantages of the invention have been accomplished. However, it will also be apparent that many changes may be made in the arrangement of parts shown and described without departing from the spirit of the invention. Therefore, it is to be understood that all matter shown or described should be interpreted as illustrative and not in a limiting sense.

I claim:

1. An abrading tool of the character described comprising a pair of annular abrading elements having different abrading characteristics and disposed one within the other, said abrading elements being coaxial with one thereof being retractable and extendable with respect to the other, and said abrading elements being provided on their adjoining sides with interfitting scallops extending alternately across a given path of generation whereby said respective elements at a given angular position of adjustment of the tool are capable of generating curved surfaces of substantially equal radii.

2. An abrading tool for abrading the surface of an article along a predetermined path of generation comprising a pair of coaxial simultaneously rotatable supporting members disposed telescopically one within the other and each having thereon an annular abrading member, said abrading members being disposed in coaxial intimate relation one within the other and being provided on their adjoining sides with interfitting scallops extending alternately across said path

of generation, and means for moving one of said supporting members longitudinally of its axis to extend or retract the abrading surface of the annular abrading member thereon axially relative to the abrading surface of the other annular abrading member whereby said abrading members may be selectively extended into abrading position.

3. An abrading tool for generating a curved surface on an article comprising a pair of coaxial supporting member disposed telescopically one within the other and each having thereon an annular abrading member, said abrading members being disposed in intimate relation one within the other, said supporting members adapted to be rotated simultaneously about their common axis to cause said abrading members to individually abrade an article when selectively located in engagement therewith, the adjoining sides of said abrading members being provided with interfitting scallops extending alternately across a given path of generation whereby as the tool is rotated the abrading portions of the scallops of the selected annular abrading member will abrade the surface of said article when positioned thereupon.

4. An abrading tool for generating a curved surface on an article comprising a pair of annular abrading elements having different abrading characteristics and disposed one within the other, said abrading elements being coaxial and simultaneously rotatable with one thereof being retractable and extendible with respect to the other, and said abrading elements being provided on their adjoining sides with interfitting scallops extending alternately across a given path of generation whereby said respective elements at a given angular position of adjustment of the tool are capable of generating curved surfaces of substantially equal radii, said scallops being of controlled curved contour shapes whereby as the tool is rotated the leading edges of the abrading portions of the scallops will approach the surface area to be abraded at an acute angle to the tangent of said path of generation at the point at which said leading edges cross said path of generation.

5. An abrading tool for generating a curved surface on an article comprising a pair of coaxial supporting members disposed telescopically one within the other and each having thereon an annular abrading member, said abrading members being disposed in intimate relation one within the other, said supporting members adapted to be rotated simultaneously about their common axis to cause said abrading members to individually abrade an article when selectively located in engagement therewith, the adjoining sides of said abrading members being provided with interfitting scallops extending alternately across a given path of generation whereby as the tool is rotated the abrading portions of the scallops of the selected annular abrading member will abrade the surface of said article when positioned thereupon, said scallops being of controlled curved contour shapes whereby as the tool is rotated the leading edges of the abrading portions of the scallops will approach the surface area to be abraded at an arcuate angle to the tangent of said path of generation at the point at which said leading edges cross said path of generation.

6. An abrading tool for generating a curved surface on an article comprising a sleeve having a first annular abrading member on one end

thereof, a support within said sleeve having a second annular abrading member thereon disposed in intimate relation with the inner side of said first annular abrading member, said support being coaxial with said sleeve and adapted to be rotated simultaneously therewith about their common axis to cause said abrading members thereon to abrade an article when in engagement therewith, means for moving said support longitudinally of said axis to retract or extend the abrading surface of said second annular abrading member axially relative to the abrading surface of said first annular abrading member whereby said abrading surfaces may be selectively extended into abrading position, the adjoining sides of said abrading members being provided with irregular contours in the form of interfitting scallops extending alternately across a given path of generation, said scallops being of curved contour shape whereby as the tool is rotated the leading edges of the abrading portions of the scallops will approach the surface area to be abraded at an acute angle to the tangent of said path of generation at the point at which said leading edges cross said path of generation.

7. In abrading apparatus of the character described embodying a base having a work supporting device thereon for rotatably supporting an article to be abraded and a tool supporting head for rotatably carrying a tool for abrading said article, an abrading tool carried by said head comprising a sleeve having a first annular abrading member on one end thereof, a support within said sleeve having a second annular abrading member thereon disposed in intimate relation with the inner side of said first annular abrading member, said support being coaxial with said sleeve and adapted to be rotated simultaneously therewith about their common axis to cause said abrading members thereon to abrade an article when in engagement therewith, means for moving said support longitudinally of said axis to retract or extend the abrading surface of said second annular abrading member axially relative to the abrading surface of said first annular abrading member whereby said abrading surfaces may be selectively extended into abrading position, the adjoining sides of said abrading members being provided with irregular contours in the form of interfitting scallops extending alternately across a given path of generation, said scallops being of curved contour shape whereby as the tool is rotated the leading edges of the abrading portions of the scallops will approach the surface area to be abraded at an acute angle to the tangent of said path of generation at the point at which said leading edges cross said path of generation.
